The schedule referred to in these Letters Patent and making part of the same.

To all whom it may concern:

Be it known that I, James L. Ray, of East Haddam, in the County of Middlesex and State of Connecticut, have invented a new design for a Coffin Handle, and I do hereby declare that the following is a full, clear and exact description of the same, reference being had to the accompanying drawing forming part of this specification, in which

Figure 1 is a front view of the design.

Figure 2 is a transverse vertical section of the same.

The peculiar feature of my design consists in the form of the profile of the handle represented in figure 1 of the drawing. The external profile of the sides commencing at the top is nearly straight for a short distance as shown at a, a, thence expanding with salient curvature, as shown at b, b, to within a short distance from the bottom where the curvatures re-enter, as shown at c, c, slightly expanding outward again to form nearly sharp corners, d, d, at the junction of the sides with the bottom. From the corners d, d, the lower edge of the external profile has hollow or re-entering curvatures e, e, uniting with a long salient curvature f, the most prominent point in which is at the middle of the length of the handle. The internal profile of the sides commencing at the top is nearly straight for a short distance downward as shown at K, K, thence expanding with hollow curvatures g, which is continued to meet the slight salient curvatures h, h, uniting with a re-entering curvature i at the centre of the bottom.

DES. 2104

2

What I claim as new and desire to secure by
Letters Patent is

The design and configuration of the profile of
a coffin handle herein described with reference to figure
1 of the accompanying drawings.
